UNITED STATES PATENT OFFICE.

JEROME E. BAUM, OF NEW YORK, N. Y.

DESIGN FOR A TOILET-ACCESSORY CONTAINER.

Application filed March 29, 1929. Serial No. 30,672. Term of patent 3½ years.

To all whom it may concern:

Be it known that I, JEROME E. BAUM, a citizen of the United States, residing at New York city, county of New York, borough of Manhattan, and State of New York, have invented a new, original, and ornamental Design for Toilet Accessory Containers, of which the following is a specification, reference being had to the accompanying drawing, forming a part thereto.

I claim:

The ornamental design for a toilet accessory container, as shown.

JEROME E. BAUM.
